UNITED STATES PATENT OFFICE.

KÄTHE HARTMANN, OF BERLIN, GERMANY.

GARMENT.

1,174,316.

Specification of Letters Patent.

Patented Mar. 7, 1916.

Application filed April 10, 1914, Serial No. 830,917. Renewed February 2, 1916. Serial No. 75,857.

To all whom it may concern:

Be it known that I, KÄTHE HARTMANN, a subject of the King of Prussia, German Emperor, and residing at Berlin, German Empire, have invented new and useful Improvements in Garments for Pregnant and Nursing Women, of which the following is a specification.

This invention relates to improvements upon garments of such a kind as are described in my pending U. S. A. application No. 790,478, filed 18. Sept. 1913, and the object of my improvements is to render the garment in question apt to be employed also as a walking dress or costume or even as a dinner or evening dress or costume, whereas the garment as described and shown in the beforementioned pending application is intended solely for use in lying-in or maternity hospitals and is consequently of simple and cheap make, allowing also of an easy cleaning and quick repair. In that garment the waist and the skirt are either made in one piece or they are otherwise firmly connected with each other. In view of the increase of the body during the time of pregnancy, that garment is provided with an appropriately adjustable girdle, there arising, of course, such folds in it as follow from the state of the respective woman. A garment of this make is sufficient for hospitals of the kind in question, as there is, in such a place, no need, of course, to cast a veil over the condition of the female body, the only requirement being that the garment permits of proper adjustment. Moreover, the garment does not enable the wearer to conceal her state, owing to its make, as mentioned. However, at home, on walks, during visits, and the like, a lady has a natural desire to cast a veil over her state as long as possible, and the garment in question has, therefore, been modified in such a manner that that desire may be complied with, the thus improved garment fitting always very well, without odd folds, the body offering merely the appearance of a little overgrowth, without an actual indication of its

state. Also in the improved garment which forms the subject matter of the present invention, the waist folds are held in place by special closing means allowing of changing the folds according to the circumference of the body, without needle and thread, but as the front of the skirt is raised in conformity with the increase of that circumference, means are provided to lower it appropriately far, as is more fully described herein-after.

Referring to the accompanying drawing, 60 the front *b* of the waist has also in this instance, like that in the pending application, a rather long closure *d* on the left side, and a somewhat shorter closure *e* on the right side. The waist *b* and the skirt *l* are 65 firmly connected with each other at the sides and at the back, but where these two parts are not so connected, there a plurality of rows of spring buttons is provided, one row above, or below, the other, as shown. The 70 male parts of the buttons are affixed to the waist and the female parts are affixed to the skirt. These parts are pressed upon the male parts first of the upper row, afterward of the second row, and finally of the 75 third row, if there are but three such ones, as in the drawing. The breadth of the girdle *g* is such that at any rate all buttons are completely covered.

Having now described my invention, what 80 I desire to secure by a patent of the United States is:

In a garment, the combination, with a waist, of a skirt permanently connected with said waist at the back and at the sides; 85 means for adjustably and detachably connecting the front part of the skirt with the front part of the waist, and a girdle; said means being arranged in a plurality of rows situated one below the other, and said girdle 90 being adapted to cover all said rows.

KÄTHE HARTMANN.
